(**) Term: **14 Years**

(57) **CLAIM**

(21) Appl. No.: **29/169,471**

The ornamental design for an electronic sound recording and sound reproducing device with mirror for a baby, as shown.

(22) Filed: **Oct. 21, 2002**

DESCRIPTION

(30) **Foreign Application Priority Data**

May 7, 2002 (WO) DMA/005 712

FIG. 1 is a perspective view showing my new design;

(51) LOC (7) Cl. **14-01**

FIG. 2 is a front elevational view thereof;

(52) U.S. Cl. **D14/167**

FIG. 3 is a rear elevational view thereof;

(58) **Field of Search** D6/300-309; D14/496, D14/168, 167, 188-189, 207; 455/344, 350, 351

FIG. 4 is a left side elevational view thereof;

FIG. 5 is a right side elevational view thereof;

FIG. 6 is a top plan view thereof; and,

FIG. 7 is a bottom plan view thereof.
